HOISTING APPARATUS

Warren K. Thorson and Archie R. McLellan, Dallas, Tex., assignors to Ideco Inc., a corporation of Ohio

Filed Mar. 28, 1956, Ser. No. 574,439

6 Claims. (Cl. 254—145).

This invention relates to novel hoisting apparatus for use with a drilling mast or the like. In one of its aspects, this invention relates to such apparatus which is especially well suited for use at offshore drilling locations and, more particularly, in connection with masts which are tiltable in a vertical plane.

Masts for use in drilling and the performance of other operations upon wells are conventionally provided with hoisting apparatus which includes a crown block on the upper end of the mast and a traveling block suspended from the crown block by a line extended between sheaves on the blocks. The "dead" end of this line is secured to a point fixed with respect to the support or platform for the mast, and the "fast" end thereof is connected to a power source in the form of a rotatable drum of the "drawworks," whereby the traveling block and equipment carried therefrom may be raised or lowered.

One of the more recent innovations in the industry has been the portable type mast which is conveyed on a carrier in a substantially horizontal position and then raised upright at the drilling site. In many of these masts, such as the one which is shown on pages 2480-2484 of the 1954-55 edition of the Composite Catalog of Oil Field and Pipeline Equipment, the hoisting apparatus is also used in raising and lowering the mast between upright and lowered positions.

It has been conventional practice, in connection with portable as well as other types of masts, to dispose the drawworks drum in substantial alignment with the crown and traveling blocks such that the fastline is at no time during hoisting, or, in the case of portable masts, during raising and lowering, caused to be misaligned with the sheaves of the crown block. In the case of a portable mast of the type abovementioned, the drawworks is disposed on the side of the lower end of the mast opposite that toward which the mast swings into lowered position, so as to obtain the optimum distribution of forces in raising and lowering the mast.

Certain improvements in mast construction and drilling techniques have made this conventional arrangement objectionable. For example, when a mast of the portable type is mounted upon a floatable support for use at offshore locations, spacing and loading considerations may dictate against placement of the drawworks in substantially the plane of swinging movement of the mast. That is, a conventionally arranged drawworks may be found to require too long a "drilling slot" on the floatable support or, on the other hand, to make the support unstable and subject to over-turning by an over-concentration of weight toward one edge thereof.

Still further, in the case of tilttable masts of the character shown in a co-pending application of W. K. Thorson, entitled "Improvements in the Handling of Equipment Laterally of a Well Location," Serial No. 554,765 filed December 22, 1955, the mast may be swung from an upright position, and in a direction away from its lowered position, to a tilted position in which it may be used as a crane boom in handling equipment laterally of the well.

2

location. If the hoisting apparatus normally employed in drilling and performing other operations on the well were also to be used in suspending equipment in the tilted position of the mast, it might become necessary to shift the drawworks from first one to another side of dead center of the mast in order to obtain the proper distribution of hoisting forces, as previously mentioned.

An object of this invention is to provide novel hoisting apparatus for use with a tilttable mast of the character above-described, which apparatus is so constructed and arranged that the drawworks may be fixedly located on the platform for the mast.

Another object is to provide hoisting apparatus for use with a mast which is swingable in a vertical plane, wherein the drawworks may be disposed to one side of such plane without misalignment of the fastline with the sheaves of the crown block.

A further object is to provide, particularly for use with a mast swingable in a vertical plane at an offshore drilling location, hoisting apparatus in which the drawworks is disposed to the side of the mast and the fast end of the line extending between the crown block and drawworks drum is caused to be spooled about the drum substantially uniformly of the length thereof, despite the position of the mast in its vertical plane of swinging movement and without misalignment of the line with the sheaves of the crown block.

Still another object is to provide, in a mast swingable in a vertical plane of movement, hoisting apparatus in which the traveling block is swingable in substantially the plane of movement of the mast and wherein the fast end of the line is so directed and guided that it may be extended down the outside of the mast for uniformly spooling about a drawworks drum which is located to one side of the mast and with its axis of rotation disposed substantially parallel to said vertical plane of swinging movement.

Yet a further object is to provide, for use with apparatus of the character described, a novel device for automatically spooling a line about a drawworks drum substantially uniformly of the length thereof.

Other and further objects of this invention will appear as the description proceeds.

In the accompanying drawings forming a part of the instant specification and wherein like reference numerals are used in the various views to indicate like parts.

Fig. 1 is a side elevational view of a portable and tilttable mast in an upright position for drilling and performing other operations on a well at an offshore location, and showing, in broken lines, the mast in its lowered, substantially horizontal position as well as in its tilted position for use as a crane boom in handling equipment laterally of the well location;

Fig. 2 is an end elevational view of the mast of Fig. 1 and taken from the left thereof;

Fig. 3 is a top plan view of the mast of Figs. 1 and 2;

Fig. 4 is an enlarged front elevational view of a spooling device which forms part of the novel hoisting apparatus for use with the mast of Figs. 1 to 3;

Fig. 5 is a side elevational view of the spooling device of Fig. 4, and taken from the right thereof;

Fig. 6 is an enlarged top plan view of the crown block which forms another part of the hoisting apparatus of the present invention; and

Fig. 7 is an enlarged end elevational view of a portion of the mast and hoisting apparatus, as seen from Fig. 2, and interrupted intermediate the traveling block and crown block of Fig. 6.

Referring now particularly to the drawings, and as shown and described in detail in the aforementioned publication, the mast 10 is of a type which is swingable in a

vertical plane between a lowered, substantially horizontal position in which it is supported upon a head rest 11, as shown in broken lines of Fig. 1, and an upright position, as shown in the solid line of Figs. 1 to 3, in which latter position a well may be drilled and other operations performed thereon. This mast is of substantially A frame construction so as to provide an open face (see Fig. 2) and is pivotally mounted at its lower end 12 to a platform 13 for swinging in the manner above mentioned. As fully described in the aforementioned publication and U.S. Patent 2,781,108, the mast is raised and lowered by means of a pair of raising legs 14 which are connected between the platform and the mast for movement along tracks 15 and which cooperate with the block and tackle 16 of the hoisting apparatus for forcing the legs along the tracks to the position shown, wherein they may be locked to the mast and provide a lateral support therefor.

As is conventional, the block and tackle means includes a traveling block 17 and a crown block 18, each having a plurality of sheaves between which a line 19 is extended. The dead end 20 of the line is connected to a point 21 fixed with respect to the platform 13, while the fast end 22 of the line is extended from the crown block 18 to the rotatable drum 23 of the drawworks 24 mounted on the platform 13. In this manner, the drawworks may be operated to raise and lower the traveling block 17 in hoisting equipment from the hook thereof.

The mast 10 is also tiltable, in a manner more fully described in the aforementioned co-pending application, to the broken line position of Fig. 1 wherein equipment may be handled laterally of the well location by means of the hoisting apparatus previously described. More particularly, the raising legs 14 are extendable in length, by means of a suitable mechanism 25, from the solid line position of Fig. 1 wherein they provide a lateral support for the mast in its upright position to the broken line position in which they have swung the mast to its tilted position. At this time, and as more fully described in said co-pending application, the rigid connection between the raising legs 14 and the mast is released and the mast is supported in its tilted position by means of guy lines 26 extended between the upper end of the mast and points 27 fixed with respect to the platform.

The platform 13 for the mast as well as the head rest 11 are mounted upon support 28 which may be of a type floatable upon barges or the like to an offshore location, at which location it may be fixedly located with respect to the subsurface level in any of a number of well known ways. With reference to Fig. 3, it can be seen that the platform 13 for the mast is disposed over a "drilling slot" 29 which extends inboard of one edge of the support. The broken line representation of the platform 13 illustrates the manner in which the platform may be shifted from one location to another over the slot for drilling a number of wells 30. With reference again to Fig. 1, it can be seen that this location of the platform permits the mast to be swung to the tilted position wherein equipment may be handled laterally of the well location as well as the support 28 for purposes which are described in the aforementioned co-pending application, and which need not be repeated here.

As previously mentioned, it has heretofore been the practice to dispose the drawworks substantially in the plane of swinging movement of the mast and to the side of dead center thereof opposite from the side the mast occupies in lowered position such that the drawworks 24 would conventionally be disposed on the outboard side or mouth of the drilling slot 29. However, in accordance with the present invention, the drawworks 24 is disposed to one side of the vertical plane of swinging movement of the mast, and more particularly, laterally of the lower end 12 of the mast and with the axis of rotation of its drum 23 disposed parallel to such plane of movement. The fast line 22 is extended downwardly from the crown

block 18 to the drawworks 24 along the outside of the mast 10, as best shown in Fig. 2. It will be understood that this location of the drawworks to one side of the plane will enable the slot 29 to be shortened, and will 5 further reduce the concentration of weight at the mouth of the slot adjacent one edge of the support 28. Also, it will be understood that the location of the drawworks to one side of the swinging plane of movement of the mast enables clearer vision through the open face 10 thereof.

As previously mentioned, the proper distribution of hoisting forces and other reasons have prompted the practice in the past of locating the drawworks to the side of dead center of the mast opposite that to which the mast 15 extends when in other than a vertical position. Since the tilting mast of this invention lies to one side of dead center in its lowered position and on the other side of dead center when in tilted position, adherence to such practice would mean that the drawworks would have to 20 be shifted from one side of dead center to the other.

As will now be appreciated, the location of drawworks 24 to one side of the plane of swinging movement of the mast obviates the necessity for shifting the drawworks in the manner above discussed.

25 Obviously, however, during swinging movement of the mast in its vertical plane, the fast line is caused to assume varying angular relationships with respect to the drum of the drawworks such that some means must be provided for causing it to spool about the drum substantially uniformly of the length thereof. Furthermore, the extension of the fast line down the side of the mast necessitates some means by which it may be connected between the crown block 18 and drum 23 of the drawworks without misalignment with the sheaves of the 30 crown block. That is, as shown in the drawings, the sheaves of the crown block and traveling block are normally disposed for rotation about axes perpendicular to the plane of swinging movement of the mast such that the traveling block and its hook may be swung in substantially the same plane as that of the swinging mast. It will be obvious that if some means were not provided for translating the direction of the line toward the laterally disposed drawworks 24, it would be misaligned with 35 the sheaves of the crown block.

40 For this purpose, and in accordance with the present invention, there is provided a novel spooling device, indicated in its entirety by reference character 31 and to be described in more detail hereinafter in connection with Figs. 4 and 5, and a sheave 32 on the crown block 18 which is carried for rotation about an axis substantially 45 parallel to the plane of swinging movement of the mast for directing the fast end of the line from the crown block 18 downwardly to the laterally exposed drum 23 of the drawworks 24.

50 Referring first to the novel construction of the crown block 18, as shown in Figs. 6 and 7, it will be seen to comprise a deck 33 made up of longitudinal and transverse support members and carrying thereabove a bracket 34 for rotatably supporting the fast line directing 55 sheave 32, in a manner previously mentioned. The deck 33 is in turn supported upon a water table 35 carried above the upper end of the mast and providing a bracket for rotatably supporting a plurality of sheaves 36 about an axis disposed substantially perpendicularly 60 to the plane of swinging movement of the mast. As shown in Fig. 7, the line 19 of the block and tackle means 16 is extended between the sheaves 36 of crown block 18 and a plurality of sheaves 37 of a conventional type traveling block 17, which latter sheaves are also 65 disposed for rotation about an axis substantially perpendicularly to the plane of swinging movement of the mast such that, as the mast is tilted, the traveling block 17 may swing outwardly therefrom in substantially the 70 same plane of movement as the mast.

With more particular reference to the construction of

the crown block 18, it will be seen from Figs. 6 and 7 that the fast line 22 extends upwardly from the drawworks drum along the outside of the mast 10 to the sheave 32. As is apparent from the drawings, this sheave 32 is so carried by the crown block as to direct the fast end of the line toward the drum of the drawworks. That is, it can be seen that in any position of the mast in its vertical plane of swinging movement, the fast end of the line will be so directed such that it is not misaligned with the sheaves 36. From the sheave 32 the fast end of the line extends downwardly to the sheaves 37 of the traveling block so that it may be extended back and forth between the sheaves 37 and those 36 of the crown block in a conventional manner. As will also be seen from Figs. 6 and 7, the fast end of the line 22 is directed down toward the rightmost sheaves of the crown and traveling blocks, while the dead line 20 extends downwardly from the leftmost sheave of the sheaves 36 of crown block 18.

Referring now to the novel spooling device 31, it will be seen to comprise a sheave 38 which is swivelly mounted adjacent the drawworks 24 for engaging the fast line 22, as shown by broken lines in Fig. 5, in such a manner as to cause it to spool uniformly along the length of drawworks drum 23. Specifically, it is preferred that the sheave 38 comprise a snatch block of conventional construction such that the fast line 22 may be quickly disengaged therefrom to permit drilling of the well and the performance of other operations thereon in the upright position of the mast without the use of the spooling device 31. That is, it will be found that the spooling device is required only in raising and lowering or in tilting the mast in which case it may be preferred not to use same in the upright position of the mast.

Referring now particularly to Figs. 4 and 5, the sheave 38 is swivelly mounted upon a support 39 on the platform 13, which support is located intermediate the drawworks and the lower end of the mast so that the sheave 38 may engage the fast line 22 in the manner shown by broken lines in Fig. 5. Upon the support 39 is mounted a frame 40 carrying a pair of parallel guides 41. Slidable over the guides 41 is a carriage 42 from which the sheave 38 is suspended by means of a well known type of swivel connection 43. Thus, upon sliding movement of carriage 42 longitudinally on guides 41, the fast line 22 may be engaged by the sheave 38 so as to spool the line uniformly along the length of the drawworks drum 23.

More particularly, carriage 42 is power actuated such that it may be reciprocated along the guides 41 to perform the spooling operation automatically. This means for power actuation of carriage 42 comprises a piston rod 44 connected at one end to carriage 42 and at its opposite end to a piston 45 slidable within a power cylinder 46 carried from the support 39, as shown in Fig. 4. As shown diagrammatically in Fig. 4, fluid may be introduced from any suitable source under pressure to opposite sides of the piston 45 through lines 47 and 48, and these lines may be connected to a four-way valve 49 for alternately exposing one side of the piston to the source (not shown) of fluid pressure, while exhausting the opposite side.

Preferably, this power actuation of carriage 42 supporting the sheave 38 is synchronized with the speed at which the line is spooled about the rotatable drum 23. Obviously, this may be done by manual operation of the valve 49 or by any suitable automatic means. Also, of course, equivalent mechanical means may be employed in lieu of the fluid actuator shown and described.

From the foregoing it will be seen that this invention is one well adapted to attain all of the ends and objects hereinabove set forth, together with other advantages which are obvious and which are inherent to the apparatus.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. In combination with a mast, means mounting the mast on a platform for swinging movement through a substantial arc and in a vertical plane, a crown block at the upper end of the mast, a traveling block suspended by a line from the crown block, the crown and traveling blocks having sheaves receiving said line and rotatable about axes perpendicular to the plane of swinging movement of the mast, drawworks having a rotatable drum on the platform to one side of said plane, the dead end of said line being secured to a point fixed with respect to the platform and the fast end being attached to the drawworks drum for raising and lowering the traveling block, another sheave fixedly mounted on the crown block for directing the fast end of the line from said crown block toward said drawworks without misalignment with said first-mentioned sheaves, and means engageable with said fast end of the line adjacent the drawworks and movable longitudinally along the drum of the drawworks to guide said line onto and from the drum of the drawworks substantially uniformly of the length thereof and at a substantially uniform angle with respect to the drum while the mast is in different swinging positions in said arc.
2. Apparatus of the character defined in claim 1, wherein said means engageable with said line includes a swivelly mounted sheave movable along a path longitudinally of the drawworks drum.
3. Apparatus of the character defined in claim 2, wherein said swivelly mounted sheave is a snatch block.
4. In combination with a mast, means mounting the mast on a platform for swinging movement through a substantial arc and in a vertical plane, a crown block at the upper end of the mast, a traveling block suspended by a line from the crown block, the crown and traveling blocks having sheaves receiving said line and rotatable about axes perpendicular to the plane of swinging movement of the mast, drawworks on the platform to one side of the mast and its vertical plane of swinging movement, and including a drum disposed for rotation about an axis substantially parallel to said plane, the dead end of said line being secured to a point fixed with respect to the platform and the fast end being attached to the drawworks drum for raising and lowering the traveling block, another sheave carried on the crown block for rotation about an axis parallel to said plane of swinging movement for directing said fast end of the line down the outer side of the mast between the crown block and drawworks drum, and means engageable with said fast end of the line intermediate the directing sheave and drawworks drum and being movable longitudinally of the drum to guide the line onto and from said drawworks drum substantially uniformly of the length thereof and at a substantially uniform angle with respect to the drum when the mast is swung to various positions in said arc.
5. Apparatus of the character defined in claim 4, wherein the means engageable with the fast line includes a sheave swivelly mounted adjacent the drawworks for movement longitudinally of the drum thereof.
6. Apparatus for use in drilling and performing other operations on a well comprising a platform, a mast, means mounting the mast on the platform for swinging movement in a substantially vertical plane from a re-

clining position to a substantially vertical position, block and tackle means carried by the mast, means connectible to the block and tackle means to raise the mast from said reclining to said vertical position responsive to manipulation of the block and tackle means, a draw- 5 works including a drum situated laterally to one side of the mast and of said vertical plane, a fast line extending from the upper portion of the mast and connecting the drawworks to the block and tackle means, a device for guiding the fast line onto the drum of the draw- 10 works, and means for moving said device back and forth along the drawworks drum to guide the fast line substantially uniformly thereon along the length of the drum and at a substantially uniform angle with respect to the drum while the mast is moving from said reclining position to said vertical position. 15
